UNITED STATES PATENT OFFICE.

CORNELIUS CALLAHAN, OF CHELSEA, MASSACHUSETTS.

CUT-OFF FOR VALVES.

SPECIFICATION forming part of Letters Patent No. 299,734, dated June 3, 1884.

Application filed October 6, 1883. (No model.)

To all whom it may concern:

Be it known that I, CORNELIUS CALLAHAN, of Chelsea, county of Suffolk, State of Massachusetts, have invented an Improvement in Cut-Offs for Valves, of which the following description, in connection with the accompanying drawings, is a specification, like letters on the drawings representing like parts.

My invention relates to a cut-off for water and other pipes; and it consists, primarily, of a shell or case having a valve composed of two disks connected by a thin web, which is packed at its working edges.

My invention consists, secondly, of a shell or case having preferably a stepped seat, and a valve composed of two disks held together by a thin web packed at its edges, combined with a packing-annulus and a threaded ring or plate adapted to hold the valve in place.

The object of my invention is to provide a strong, compact, tight-fitting, valve, which, when open, offers the minimum of obstruction to the flow of water through the shell or case.

Figure 1 is a longitudinal vertical section of my improved valve, showing all the parts. Fig. 2 is a horizontal section thereof, to clearly illustrate the packed meeting edges of the thin web of the valve. Fig. 3 represents the valve removed from the shell or case in which it is to rotate.

A A' mark two disks, held together by a thin web, A², and having a shank, a, projecting from the upper disk, A, the whole forming a valve, which is stepped, as at b, in the closed bottom or seat B' of the shell or case B. The seat B' is recessed for the reception of a packing-annulus, C, upon which rests the lower disk, A', of the valve, the purpose being to provide a tight fit at that point where the valve is properly secured in place. The working edges of the thin web A², which hug the walls of the shell or case B, are grooved, and the grooves are filled with packing a², to prevent any possible escape of fluid when the valve is closed. A packing-annulus, D, rests

upon the upper disk, A, of the valve, which latter is firmly held in place and a tight fit made at the edges of the upper disk by means of the annular nut E, which is screwed into the open side of the shell or case, as shown, thereby pressing the packing-annulus D against the upper disk, A, and forcing the lower disk, A', against the packing-annulus C, as will be clearly understood by referring to Fig. 1. The shank a of the valve projects through a central opening in the cap F and receives a handle, a', of the usual construction. The cap, as herein shown, is interiorly screw-threaded, and engages with the nut E.

The escape of fluid when the valve is closed is provided against not only by means of the packed working edges of the web A² and the packing-rings C D, but also for the reason that the disks A A' are arranged in recesses in the shell or case, respectively above and below the line of flow of the fluid in the pipes joined with the said shell, and the peripheries of the said disks meet the walls of said shell or case to further guard against the escape of fluid.

I claim—

1. The cut-off composed of a case or shell and disks A A', held together by a thin web, A², having its edges provided with packing, substantially as described.

2. The combination, with the case or shell, which is closed at its bottom and provided with the packing-annulus C, of the valve composed of the disks A A', and web A², having the packed working edges a², the said valve being stepped in the bottom of the shell or case, as described, and with the packing-annulus D and retaining-nut E, substantially as set forth.

In testimony whereof I have signed my name to this specification in the presence of two subscribing witnesses.

CORNELIUS CALLAHAN.

Witnesses:

Jos. P. LIVERMORE,
B. J. NOYES.
